(57) **CLAIM**

The ornamental design for a wireless networking device, as shown and described.

DESCRIPTION

A portion of the disclosure of this patent document contains or may contain material which is subject to copyright protection by Sonos, Inc. The copyright owner has no objection to the photocopy reproduction by anyone of the patent document for the patent disclosure in exactly the form it appears in the USPTO patent file or records, but otherwise reserves all copyright rights whatsoever.

FIG. 1 is an isometric view of a wireless networking device. FIG. 2 is a front view of the wireless networking device of FIG. 1.

FIG. 3 is a rear view of the wireless networking device of FIG. 1.

FIG. 4 is a side view of the wireless networking device of FIG. 1.

FIG. 5 is another side view of the wireless networking device of FIG. 1.

FIG. 6 is a top view of the wireless networking device of FIG. 1; and,

FIG. 7 is a bottom view of the wireless networking device of FIG. 1.

In the drawing the claimed design is defined by the shaded surfaces; the broken lines depict unclaimed environment that forms no part of the claimed design.
